CLAIM

The ornamental design for a corner radius template having a slot that receives a template piece, as shown and described.

DESCRIPTION

FIG. 1 is an elevation view of the top side of the corner radius template having a slot that receives a template piece, the view showing the top side widen for a distance, then

narrow for a distance beginning at the middle of the top side, and finally the view showing the top side terminating in a curved corner;

FIG. 2 is an elevation view of the bottom side of the corner radius template having a slot that receives a template piece, the view showing the bottom side widen for a distance, then narrow for a distance beginning at the middle of the bottom side, and finally the view showing the bottom side terminating in a curved corner;

FIG. 3 is an elevation view of the left side of the corner radius template having a slot that receives a template piece, the view showing the corner radius template having a generally flat bottom side that is configured to sit upon a work surface;

FIG. 4 is an elevation view of the right side of the corner radius template having a slot that receives a template piece, the view showing the corner radius template having a generally flat bottom side that is configured to sit upon a work surface;

FIG. 5 is an elevation view of the front side of the corner radius template having a slot that receives a template piece, the view showing the corner radius template having a slot in its front side that is configured to receive a template piece therein, the view showing the front side of the corner radius template having a mechanism for removably securing various template pieces;

FIG. 6 is an elevation view of the back side of the corner radius template having a slot that receives a template piece, the view showing the corner radius template having a generally flat bottom side that is configured to sit upon a work surface;

FIG. 7 is a perspective view of the top side of the corner radius template having a slot that receives a template piece, the view showing the corner radius template having a slot in its front side that is configured to receive a template piece therein;

FIG. 8 is a perspective view of the top side of the corner radius template having a slot that receives a template piece, the view showing a template piece secured in a slot on the front side of the corner radius template; the template piece being removable from the corner radius template;

FIG. 9 is a perspective view of the bottom side of the corner radius template having a slot that receives a template piece, the view showing the corner radius template having a slot in its front side that is configured to receive a template piece therein, the view showing the slot having a mechanism for removably securing various template pieces, and finally the view showing a template piece being removably secured in the slot on the front side of the corner radius template;

FIG. 10 is a perspective view of the top side of the corner radius template having a slot that receives a template piece, the view showing the corner radius template having a slot in its front side that is configured to receive a template piece therein;

FIG. 11 is a perspective view of the top side of the corner radius template having a slot that receives a template piece, the view showing the corner radius template having a slot in its front side that is configured to receive a template piece therein;

FIG. 12 is a perspective view of the top side of the corner radius template having a slot that receives a template piece, the view showing the corner radius template having a slot in its front side that is configured to receive a template piece therein;

FIG. 13 is a perspective view of the top side of the corner radius template having a slot that receives a template piece, the view showing the corner radius template having a slot in its front side that is configured to receive a template piece therein;

FIG. 14 is a perspective view of the top side of the corner radius template having a slot that receives a template piece, the view showing the corner radius template having a slot in its front side that is configured to receive a template piece therein;

FIG. 15 is a perspective view of the top side of the corner radius template having a slot that receives a template piece, the view showing the corner radius template having a slot in its front side that is configured to receive a template piece therein; and,

FIG. 16 is a perspective view of the top side of the corner radius template having a slot that receives a template piece, the view showing the corner radius template having a slot in its front side that is configured to receive a template piece therein.

Any dashed lines shown represent the environment and represent unclaimed subject matter and form no part of the claimed design.
